US00D739384S

(12) **United States Design Patent**
Won et al.

(10) **Patent No.:** US D739,384 S
(45) **Date of Patent:** ** Sep. 22, 2015

(54) **REMOTE CONTROLLER**

- (71) Applicant: **Samsung Electronics Co., Ltd.**, Suwon-Si, Gyeonggi-Do (KR)
- (72) Inventors: **Dong Hee Won**, Seoul (KR); **Kyubok Lee**, Seoul (KR); **Minhee Lee**, Seoul (KR)
- (73) Assignee: **Samsung Electronics Co., Ltd.**, Gyeonggi-do (KR)
- (**) Term: **14 Years**

(21) Appl. No.: **29/460,360**

(22) Filed: **Jul. 10, 2013**

(30) **Foreign Application Priority Data**

- Jan. 14, 2013 (KR) 30-2013-0002278
- (51) **LOC (10) Cl.** 14-03
- (52) **U.S. Cl.**
USPC **D14/218**
- (58) **Field of Classification Search**
USPC D14/218, 137-139, 174, 151, 191-193, D14/299, 167, 168, 221; D13/168, D13/162-164; D21/512-517, 566; D10/104, 106; 455/352-355, 455/151.1-151.4, 128, 347, 90.3; 348/114, 348/734

(57) **CLAIM**

The ornamental design for a remote controller, as shown and described.

DESCRIPTION

FIG. 1 is the front/left-side/top perspective view of a remote controller showing our new design;
FIG. 2 is the front elevational view thereof;
FIG. 3 is the rear elevational view thereof;
FIG. 4 is the left-side elevational view thereof;
FIG. 5 is the right-side elevational view thereof;
FIG. 6 is the top-side plan view thereof; and,
FIG. 7 is the bottom-side plan view thereof.
The broken lines shown in the drawings represent unclaimed portions.
